PUNCH AND DIE MECHANISM

Edmund F. Shalla, Baltimore, Md., assignor to
Western Electric Company, Incorporated, New
York, N. Y., a corporation of New York

Application September 3, 1941, Serial No. 409,365

4 Claims. (Cl. 164—86)

This invention relates to punch and die mechanisms and particularly to a shedder for compound type punch and die mechanisms.

In a compound type punch and die mechanism, the article is usually formed complete in one step and after being blanked from the material and/or perforated is reinserted in the opening in the material and remains therein during the advance of the material and until removed by suitable means. To return the blanked article to the material there is provided in one type of compound punch and die mechanism an elastically mounted shedder reciprocable in the die aperture. During the blanking operation the shedder yields as the blank moves into the die aperture and during the return movement of the blanking punch the shedder follows and presses the blanked article into the opening in the material from which it was punched. In the punching of articles such as washers or nuts from some materials, for instance, brass, fine brass dust slivers or particles are produced which have a tendency to work their way between the sliding or bearing surfaces of the shedder and cause it to bind or deleteriously score the same. This results in increased maintenance on the mechanism and frequent delays in production.

An object of the present invention is to overcome the above objectionable features by providing a simple and practical shedder so constructed that scoring of its bearing surfaces or binding thereon is substantially eliminated.

In attaining this object, in one embodiment of the invention as applied to a compound punch and die mechanism for blanking washers there is provided a tubular shedder having formed in its outer and inner peripheral surfaces continuous helical grooves. The grooves are semi-circular in cross-section and the inner grooves are spaced substantially closer together than the outer grooves and each groove is open at its upper end to receive fine dust sliver particles produced in the blanking operation. In practice any particles tending to get between the inner and outer peripheral surfaces of the shedder and their bearing surfaces on the perforator and the blanking die aperture, respectively, are lodged in the grooves, thus eliminating deleterious scoring of the bearing surfaces or binding between the shedder and its bearing surfaces.

Other objects and advantages of the invention will be understood by reference to the following specification and accompanying drawings, in which

Fig. 1 is a fragmentary vertical sectional view, partly in elevation, through a compound punch and die mechanism which includes a shedder constructed in accordance with one embodiment of this invention, the mechanism being shown in its normal position;

Fig. 2 is a plan view thereof with the punch removed;

Fig. 3 is a fragmentary view similar to Fig. 1 showing the punch and shedder after a blanking operation and before returning to their normal positions;

Fig. 4 is an enlarged detail vertical sectional view, partly in elevation, of the improved shedder, and

Fig. 5 is a plan view of the shedder.

In the drawings, this invention is illustrated as used in connection with a simple form of compound type punch and die mechanism, shown fragmentarily, and indicated in general at 10. By way of illustration, the mechanism 10 is effective to blank washers 11, one at a time, from brass strip material 12. The mechanism 10 comprises a bolster plate 13 which is fixedly supported upon a punch press frame 14 and a reciprocatory ram (not shown) of the press carries a hollow punch 15, shown fragmentarily.

Fixed to the upper surface of the bolster plate 13 is a die plate holder 16 carrying a die plate 18 having a die aperture 19 which in cooperation with the reciprocatory punch 15 blanks the washers 11 from the strip 12. The strip 12 rests upon the upper surface of the die plate 18 and is intermittently advanced after each punching operation by suitable mechanism in a manner well known in the art to present a new surface to the punch 15. Arranged above and with a suitable clearance from the strip 12 is an apertured stripper plate 20 supported upon the dial plate 18 by a plurality of clamping dogs 21, the strip in its advance being guided by the dogs and the stripper plate.

Secured to the die plate holder 16 within a recess in its bottom surface is a plate 24 to which is fixed a perforating punch 25 which extends upwardly from the plate into an aperture 26 in the die plate holder. The perforating punch 25 is axially aligned with the die aperture 19 and the blanking punch 15 and a reduced upper end of the punch terminates in the plane of the upper surface of the die plate 18.

A tubular shedder embodying the features of this invention is indicated at 27 and surrounds the perforating punch 25, and its upper end surface normally lies in the plane of the upper surface of the die plate 18. The shedder 27 in the operation of the punch and die mechanism 10 slides on the perforating punch 25 and the peripheral wall of the die aperture 19 and is closely fitted thereto. At its lower end the shedder 27 is formed with a supporting flange 28 which rests upon a yieldable plate 31 which is fitted closely to the peripheral wall of the die plate holder aperture 26. The plate 31 through which extends the upper reduced end of the perforating punch 25 rests upon a plurality of plunger rods 32 ar-

ranged to slide in apertures formed in the plate 24, the bolster plate 13 and an attached block 34.

At their lower ends the plunger rods 32 engage the upper surface of a plate 35 which is spaced from a similar plate 36 by a block of rubber 37. The plates 35 and 36 and the block of rubber 37 are attached as a unit to the block 34 by a screw 38 which extends therethrough and is threaded in the block 34, the lower end of the screw having threaded thereon a pair of nuts 39. By adjusting the nuts 39 on the screw 38 the yieldability of the rubber block 37 may be varied.

Referring particularly to Figs. 4 and 5, the improved shedder 27 has formed in its outer and inner peripheral surfaces helical grooves 41 and 42, respectively. The grooves 41 and 42 in the present embodiment are semi-circular in cross-section and each is a continuous groove extending from the upper end of the shedder to the upper surface of the flange 28. As shown, the upper ends of the grooves 41 and 42 are open at the upper end surface of the shedder as indicated at 43 and 44, respectively, for a purpose to be presently described. In order not to deleteriously weaken the wall of the shedder 27 by the forming therein of the grooves 41 and 42 the helices of the outer groove 41 are spaced further apart than the helices of the inner groove 42. In the present embodiment the spacing is such that the outer helices are aligned with each alternate helix of the inner groove, thus providing a stronger wall to the shedder 27.

It will be apparent that in the operation of the mechanism 10 in blanking and perforating washers 11 from the brass strip material 12 that fine dust sliver particles are produced during such operation and tend to get between the inner and outer peripheral surfaces of the shedder 27 and their bearing surfaces on the perforating punch 25 and the peripheral surface of the blanking die aperture 19 and will readily find lodgement in the grooves 41 and 42, first at their open upper ends 43 and 44, respectively, and secondly therebelow along successive helices of the grooves. Thus the dust particles or slivers are received in the grooves 41 and 42 and stored therein for subsequent removal and consequently deleterious scoring of the bearing surfaces of the shedder or the binding thereof is eliminated.

In Fig. 1 the blanking punch 15 and the shedder 27 are in their upper positions and the punch is about to start a washer blanking operation. During a continuous downward movement of the hollow punch 15 it enters the apertured stripper plate 20, engages the strip 12 and blanks the washer 11 therefrom and in cooperation with the die aperture 19 and the stationary punch 25 simultaneously perforates it, the washer 11 being carried below the strip 12 to the position shown in Fig. 3, which illustrates the mechanism at the end of the blanking and perforating stroke. The shedder 27 yields during the blanking operation and through its connection, previously described, with the rubber block 37, the block is compressed. In the retraction of the punch 15 the rubber block 37 expands and moves the shedder 27 upwardly to its normal position (Fig. 1) during which movement the washer 11 is returned to the opening in the strip 12 from which it was punched. Each successive punching produced by the hollow blanking punch 15 and perforating

punch 25 rises into the punch 15 and is removed at its upper end by a blast of air directed by suitable means (not shown).

It is obvious that the grooves 41 and 42 formed in the shedder 27 do not necessarily have to be semi-circular in cross section, but may be V-shaped, square or of any other suitable contour. Also, a series of circular grooves may be substituted for each of the helical grooves 41 and 42, if desired.

It will be understood that the embodiment herein described is merely illustrative of the invention and one application thereof, the invention being limited only by the scope of the appended claims.

What is claimed is:

1. In a punch and die mechanism, a die having an aperture, a punch in said aperture, and a tubular shedder operable in said aperture, surrounding said punch and having an external and internal bearing on the peripheral surfaces of said die aperture and said punch, said shedder having external and internal grooves to prevent scoring of its bearing surfaces, the helices of the external groove being differently spaced between helices than the helices of the internal groove.

2. In a punch and die mechanism, a die having an aperture, a punch in said aperture, and a tubular shedder operable in said aperture, surrounding said punch and having an external and internal bearing on the peripheral surfaces of said die aperture and said punch, said shedder having external and internal continuous helical grooves open at their upper ends in the plane of the upper end surface of the shedder for receiving dust and sliver particles to prevent scoring of its bearing surfaces, the external groove having a greater spacing between helices than the helices of the internal groove.

3. A compound punch and die mechanism for punching articles from material comprising a co-operating reciprocable punch and a stationary die having an aperture for punching an article from said material during a downward movement of said punch, and means arranged below the material comprising an elastically mounted shedder member movable in said die aperture during the punching operation, said shedder member having an external groove effective for receiving dust and sliver particles to prevent scoring the wall of said die aperture.

4. A compound punch and die mechanism for punching articles from material comprising an upper co-operating reciprocable punch and a stationary die having an aperture for punching an article from said material during a downward movement of said punch, a perforating punch below the material, and means arranged below and abutting the material for returning the punched article into the material comprising a tubular elastically mounted shedder member movable in said die aperture during the punching operation and surrounding said perforating punch, said shedder member having external and internal helical grooves open at their upper ends in the plane of the upper end surface of the shedder member for receiving dust and sliver particles to prevent scoring the wall of said die aperture.
